UNITED STATES PATENT OFFICE.

WILLIAM H. WILDER, OF GARDNER, MASSACHUSETTS.

DESIGN FOR AN OIL-STOVE.

SPECIFICATION forming part of Design No. 36,216, dated February 3, 1903.

Application filed December 2, 1902. Serial No. 133,648. Term of patent 14 years.

To all whom it may concern:

Be it known that I, WILLIAM H. WILDER, a citizen of the United States, residing at Gardner, Massachusetts, have invented a new, original, and ornamental Design for Oil-Stoves, of which the following is a specification.

I have illustrated my design in the accompanying drawing by a front elevation of the stove.

The leading feature of my design consists in an open-front base-section closed partially by a grating and in an upper radiating section. The base is shown at A, and surmount-

ing this is a section having an open front, (indicated at B,) this being partially closed by a perforated wall or grating C. A radiator-section D surmounts the section B.

I claim—

The ornamental design for an oil-stove herein shown and described.

In testimony whereof I affix my signature in presence of two witnesses.

WILLIAM H. WILDER.

Witnesses:

H. M. GATES,
W. W. TANDY.
